UNITED STATES PATENT OFFICE.

CHESTER W. LARNER, OF PHILADELPHIA, PENNSYLVANIA.

MEANS FOR CONTROLLING VALVES.

1,362,331.

Specification of Letters Patent. Patented Dec. 14, 1920.

Application filed March 6, 1919. Serial No. 280,939.

To all whom it may concern:

Be it known that I, CHESTER W. LARNER, a citizen of the United States, residing at Philadelphia, in the county of Philadelphia 5 and State of Pennsylvania, have invented certain new and useful Improvements in Means for Controlling Valves, of which the following is a specification.

This invention relates to pressure operated plunger bowl valves for operation with distributing systems, in which the direction of fluid flow is from the large end of the valve toward the small end, and which valves are operable in any position.

10 The principal object is to improve the system of control of valves of this type, particularly the Johnson valve for which Letters Patent No. 1,030,890, were granted to Raymond D. Johnson, July 2, 1912, and 15 more particularly such valve when discharging against substantially atmospheric pressure.

20 The nature, characteristic features and scope of the invention will more readily be understood from the following description taken in connection with the accompanying drawing, where,—

25 Figure 1 is a longitudinal sectional view of a Johnson valve embodying my improvements, and

30 Fig. 2 is a similar view of a modification.

Referring to the drawing, the numeral 5 represents a valve body or housing, which, as is usual may be an enlargement of a 35 conduit or pipe line for fluids under pressure, 6 and 7, are respectively, the fixed and telescopic plunger valve elements, the latter being afforded a seat, as is usual, on the wall of the valve body at the small end or neck 40 thereof.

Referring to Fig. 1, it will be noted that the chambered part of the plunger 7 is fully open to communication with or is co-extensive with the chambered part of the fixed 45 unit 6, so that there is formed a "closing" chamber 8 to which pressure is supplied through a port 9 extending from the fixed unit or valve section 6 to a point outside the valve-body. An orifice 10 in the nose

50 of the plunger serves to discharge any accumulation of pressure in the chamber 8 when pressure supplied through port 9 is cut off, thus opening the valve and assuring the maintenance of the valve in that position. 55 Port 9 connects with control piping 11 leading to a source of pressure supply in the

pipe line above the valve or to any other source where static pressure at least equal to that in the pipe line may be obtained, there being an interposed control valve, as 60 indicated at 12.

The construction illustrated in Fig. 1 is designed for use wherever the fluid will be discharged into the open air or into an outlet connecting pipe of such size and length 65 that it will not interfere with the free flow of the jet to the extent of developing a back pressure opposed to the direction of the jet of any appreciable amount above atmosphere.

70 In order to effect a closing stroke of the plunger element 7, the control valve 12 is opened whereby pressure is supplied from the control system to the operating or closing chamber 8 sufficient to force the plunger to its seat. Evidently, the control valve and its complemental piping have an area 75 in excess of that of the orifice 10 sufficient to maintain the required static pressure in the closing chamber 8 for moving the plunger to its closed position.

75 To open the valve, the control valve 12 is closed, thus cutting off the supply of pressure to the closing chamber 8 and enabling the accumulated pressure to be discharged 80 through the orifice 10. With the plunger in the closed position, a portion 13 of its conical surface is subject to the static pressure existing in valve body 5, due to the fact that the diameter of plunger 7 is larger than 85 the diameter of its seat in the neck of the valve body 5 and this applied pressure operates to unseat the valve. The orifice 10 will continue to discharge pressure from the chamber 8 until the total closing force in 90 said chamber is less than the total opening force applied externally of the plunger when the plunger will open and finally come to rest in its fully open position, in which position it will be held by the fluid flow due 95 partly to the turning of the stream and partly to the presence of a certain amount of static pressure in the discharging jet as it passes the nose of the plunger.

100 Referring to the construction, Fig. 2, the same positive closing action prevails, but I also provide a more positive opening action for the valve. In this construction the plunger element is reduced in diameter throughout a portion of its length so as to 105 form with the fixed element an annular "opening" chamber 14 from which a pas-

sage 15 leads to a pressure supply pipe 16 forming part of the control piping 11, or leading to some other appropriate source of static pressure. Thus chamber 14 is directly and continuously connected to a source of static pressure.

With the plunger in the open position the control valve 12 is closed. The orifice 10, acts, as before noted, to discharge any accumulation of pressure in the closing chamber 8, thereby eliminating any closing force. The opening chamber 14 being connected directly to a source of static pressure is of course under a positive pressure and serves to open the plunger and to hold it in the open position as long as the control valve 12 is closed.

In order to seat the plunger, the control valve 12, is opened whereupon a positive pressure is established in the closing member 8. This positive closing pressure is greater than the opening force prevailing in chamber 14 plus the opening force applied externally of the nose of the plunger by the turning of the stream and by the pressure of static pressure in the flowing fluid. Hence, the plunger is forced to its seat.

I claim:—

1. In a valve comprising a body and fixed

and movable plunger valve elements having a single chamber between their heads and a fluid way around them and of which the body affords a seat for the movable element, the combination of provisions responsive to fluid pressure and operative to unseat the movable element by reduction of pressure in said single chamber, an orifice provided in the movable element and open for limited discharge, a connection for supplying pressure to the interior of the movable element in excess of the discharge to close the valve, and means for throttling the connection to permit the valve to open, substantially as described.

2. In a valve the combination of a hollow plunger provided with an open orifice for continuously discharging pressure from the interior of the plunger, means for supplying pressure to the interior of the plunger in excess of the pressure discharged for closing the valve, devices for throttling said pressure supply means to permit of the opening of the valve, and means for exerting fluid pressure on the movable plunger to open the valve, substantially as described.

In testimony whereof I affix my signature.

CHESTER W. LARNER.
